CLAIM

The ornamental design for a leather article with surface pattern, as shown and described.

DESCRIPTION

The single FIGURE is a front view of a leather article with surface pattern showing my new design.

The portions of the design shown in broken lines do not form part of the claimed design. The claim is directed to the solid line, with the space between the solid line and the outer boundary, shown in broken line, does not form part of the claimed design.

1 Claim, 1 Drawing Sheet
